W. A. SMITH

VALVE FOR ROCK DRILLS

Filed Nov. 20, 1926

FIG. 2.

FIG. 1.

INVENTOR.
William A. Smith
BY *Herbert S. Ogden*
HIS ATTORNEY.

Patented Jan. 17, 1928.

1,656,541

UNITED STATES PATENT OFFICE.

WILLIAM A. SMITH, OF SAYRE, PENNSYLVANIA, ASSIGNOR TO INGERSOLL-RAND COMPANY, OF JERSEY CITY, NEW JERSEY, A CORPORATION OF NEW JERSEY.

VALVE FOR ROCK DRILLS.

Application filed November 20, 1926. Serial No. 149,576.

This invention relates to rock drills, but more particularly to a spool type distributing valve for fluid actuated rock drills of the hammer type.

5 An object of the invention is to obtain a substantial reduction of the pressure fluid admitted to one end of the valve chamber for throwing the valve in one direction preparatory to the admission of pressure fluid 10 to the opposite end of the valve chamber for reversing the valve.

Other objects will appear hereinafter.

The invention consists of the combination of elements and features of construction substantially as hereinafter described and claimed and illustrated in the accompanying drawings, in which

Figure 1 is a diagrammatical sectional elevation of a portion of a rock drill showing the valve in position to admit pressure fluid to one end of the cylinder, and

Figure 2 is a view similar to Figure 1 showing the valve in position to admit pressure fluid to the other end of the cylinder.

25 Referring to the drawings, A designates a cylinder having a chamber B in which is disposed a reciprocating hammer piston C. The piston C has a plain reduced forward extension D slideable in a bore in the 30 front end of the cylinder A to deliver blows of impact to a drill steel E supported in this instance by the front end of the cylinder.

Disposed on the cylinder A and preferably integral therewith is a valve chest F having a valve chamber G. The valve chamber G in this instance is of uniform diameter throughout its length and extends through the valve chest. Plugs H form closures for the ends of the valve chamber G and have reduced portions J which extend into the chamber G.

The admission of pressure fluid into the chamber G is effected through a connection K communicating with a central port L in the chamber G through a passage O. Pressure fluid is conveyed to the ends of the cylinder A through supply passages P and Q leading from points forwardly and rearwardly respectively of the central port L to the front and rearward ends of the cylinder A.

Disposed within the chamber G is a distributing valve R. The valve R is in many respects like that disclosed in United States Patent No. 1,589,255 entitled Rock drill

spool valve, granted June 15, 1926, to W. A. Smith, and, accordingly has a central head S and end heads T and U for controlling the admission of pressure fluid from the chamber G through the supply passages P and Q to the ends of the cylinder.

In the present instance the end heads T and U also control one end of the valve controlling passages V and W leading from points near the ends of the valve chamber G to points on opposite sides of the center of the cylinder A. The controlling passages V and W are preferably crossed so that the front passage V communicates with the rearward portion of the cylinder A and the rearward passage W communicates with the front portion of the cylinder A. The admission of pressure fluid into the controlling passages V and W is controlled by the piston C. Front and rearward exhaust ports X and Y are formed in the valve chest F and are controlled by the end heads T and U respectively.

As in the valve disclosed in the aforementioned patent, the present valve also is provided with ports Z and b in the end heads T and U to register with the controlling passages V and W for admitting pressure fluid from the cylinder A to the ends of the valve chamber G for actuating the valve and for exhausting pressure fluid from the ends of the chamber after the valve again approaches its initial position. Additional means are provided, however, for insuring a suitable reduction in pressure of the fluid utilized for throwing the valve so that the pressure fluid admitted to the one end of the valve chamber G may more readily overcome the pressure previously admitted to the other end of the chamber. To this end leak ports c and d are formed in the heads T and U respectively, preferably between the ends of the valve and the ports Z and b.

The ports c and d are so positioned that when the valve is in its limiting positions, the leak port in that end of the valve to which pressure fluid has been admitted for actuating it will register with the valve controlling passage leading from that end.

In the operation of the device with the valve and piston in the positions illustrated in Figure 1, pressure fluid in the central port L will flow through the chamber G between the heads S and U, thence through the rearward supply passage Q to the rear-

ward end of the cylinder and will impel the piston forwardly to deliver its blow against the drill steel E. During the forward travel of the piston C, the controlling passage V will be uncovered thereby and pressure fluid from the cylinder will flow from the said passage V and through the ports Z in the head T into the forward end of the chamber G.

10 The pressure fluid thus conveyed to the front end of the chamber G will then expand and drive the valve R rearwardly and thus also move the ports Z out of registry with the passage V. At the same time, the 15 leak ports c will be moved into registry with the passage V so that there will be an immediate reduction in pressure in the front end of the chamber G. As will be seen, pressure fluid will then flow from the front end of 20 the chamber G through the passages V, the cylinder A, and thence through the supply passage Q, the valve chamber G and through the exhaust port Y to the atmosphere along with the pressure fluid in the rearward end 25 of the cylinder utilized for impelling the piston forwardly.

After the valve has been moved rearwardly, communication will be established between the inlet port L and the supply passage P, thus permitting pressure fluid to flow to the front end of the cylinder A to drive the piston C rearwardly.

As the piston proceeds on its rearward stroke, the controlling passage W will be 35 uncovered thereby and pressure fluid will then pass through said passage W and through the ports b in the head U into the rearward end of the chamber G and expanding therein will throw the valve R forwardly. By moving the valve to this position the leak ports d will be brought into registry with the passage W thus permitting the escape of a considerable portion of the pressure fluid from the rearward end of the 40 chamber G to the front end of the cylinder and thence through the supply passage P, the valve chamber G and between the heads T and S and through the exhaust port X to the atmosphere.

50 The present invention has been found to be particularly desirable in valve structures in which the valve is thrown by pressure fluid entrapped in the ends of the valve chamber and eliminates the uncertainty 55 heretofore existing in valves of this type in which ordinary leakage from the ends of the valve chamber was relied upon for relieving the pressure in one end of the chamber sufficiently to enable such pressure to be overcome by pressure fluid admitted to the opposite end of the chamber. As will be readily seen, in valves in which there is no special provision made for inducing leakage from

the ends of the chamber, the leakage will be variable, due in part to variations in the dimensions of the valve and the valve chamber and also to a considerable extent to atmospheric conditions which naturally effect the viscosity of the lubricant between the end heads of the valve and the cooperating wall of the valve chamber. The present invention entirely obviates these uncertainties and has been found to overcome the sluggish action and the undesirable fluttering frequently found in valves of this type.

I claim:

1. A fluid actuated rock drill of the hammer type, comprising a cylinder and reciprocating hammer piston, a valve chest having inlet and exhaust ports, a valve in said chest controlling both the inlet and exhaust of the cylinder and having a central head and end heads all of the same diameter, supply passages connecting the valve chest with the ends of the cylinder, valve controlling passages connecting the ends of the valve chest with ports at each side of the center of the cylinder and controlled by the piston for permitting pressure fluid under working pressure to pass alternately to the ends of the valve chest for starting the travel of the valve in one direction or the other, means for trapping the pressure fluid in one end of the valve chest and opening the other end to atmosphere, whereby the valve is thrown the balance of its travel due to the expansion of the trapped pressure fluid, and leak ports in the valve registering with the controlling passages to permit the escape of a portion of the pressure fluid utilized for throwing the valve in one direction, thus reducing such pressure fluid below working pressure preparatory to the admission of pressure fluid into the chamber for throwing the valve in the opposite direction.

2. A fluid actuated rock drill of the hammer type, comprising a cylinder and reciprocating hammer piston, a valve chest having inlet and exhaust ports, a valve in said chest having a central head and end heads all of the same diameter, valve controlling passages connecting the ends of the valve chest with ports at each side of the center of the cylinder and controlled by the piston, means for trapping pressure fluid in alternate ends of the valve chest, and leak ports cooperating with the controlling passages to permit the escape of a portion of the pressure fluid admitted to one end of the chamber for throwing the valve in one direction preparatory to the admission of pressure fluid to the other end of the chamber for throwing the valve in the opposite direction.

In testimony whereof I have signed this specification.

WILLIAM A. SMITH.
